TELEVISION RECEIVER

Ralph S. Holmes, Haddonfield, N. J., assignor to
 Radio Corporation of America, a corporation of
 Delaware

Application May 1, 1940, Serial No. 332,625

5 Claims. (Cl. 178—7.5)

My invention relates to television receivers and particularly to receivers of the type including a cathode ray tube and its associated deflecting circuits which are held in synchronism with the scanning at the transmitter by means of transmitted synchronizing pulses.

In receivers of the above-mentioned type, there is a separating tube or circuit for removing the picture signal and for passing only the synchronizing pulses to the deflecting circuits. In order to obtain proper separation, the signal applied to the separating tube should be greater than a certain minimum amplitude. Therefore, it is the usual practice to amplify the video signal before it is applied to the separating tube. Since it is generally desirable to use a separating tube of the type which requires that the synchronizing pulses be applied to its control grid with positive polarity, the use of a second synchronizing amplifier tube may be required solely to reverse polarity if conventional practice is followed.

It is an object of my invention to provide an improved television receiver of the above-described type.

Another object of my invention is to provide an improved means for and method of supplying a composite signal comprising picture signals and synchronizing signals to a separating tube or the like for removing the picture signals.

A further object of my invention is to provide an improved television circuit which is lower in cost than conventional circuits.

In a preferred embodiment of my invention the signal to be supplied to the separating tube is taken off the output circuit of a video amplifier having gain control, rather than off some preceding point such as the output circuit of the second detector. It follows that whenever the gain of the video amplifier is varied to change the picture contrast, there is a change in the amplitude of the synchronizing pulses supplied to the separating tube. This is undesirable since a separating tube operates best on signals within a certain amplitude range.

I overcome the above undesirable picture by providing the synchronizing amplifier with a suitable gain control which is ganged with the video amplifier gain control in such a way that the synchronizing amplifier output remains substantially constant even though the gain of the video amplifier is varied.

The invention will be better understood from the following description taken in connection with the accompanying drawing in which

Figure 1 is a circuit diagram of a preferred embodiment of my invention.

Figure 2 is a circuit diagram of a different embodiment of my invention, and

5 Figure 3 is a pair of curves showing the characteristics of the gain control potentiometers which are shown ganged in Figure 1.

Referring to Fig. 1 of the drawing, there is shown a portion of a television receiver designed for the reception of a television signal, such, for example, as a carrier wave which is "negatively" modulated by a composite signal consisting of picture signals and synchronizing pulses where the synchronizing pulses extend beyond "black" (i. e., to "blacker-than-black") and therefore are of greater amplitude than the picture signals. The synchronizing signals include horizontal synchronizing signals, one of which occurs at the end of each scanning line, and vertical synchronizing or framing pulses of the same amplitude as, but of greater duration than, a horizontal synchronizing pulse, a framing pulse occurring at the end of each vertical deflection.

The receiver may be of the superheterodyne type comprising a second detector 10 which supplies the above-described composite signal consisting of picture signal and synchronizing pulses to a suitable cathode ray tube 11 through a single video amplifier stage 12. Since the synchronizing pulses should be impressed upon the control electrode 13 of the cathode ray tube 11 with negative polarity in order to block the cathode ray during the return period, the second detector 10 is so connected that the synchronizing pulses appear in the detector output with positive polarity.

30 The video amplifier stage 12 in the example illustrated comprises a vacuum tube of the pentode type which has a fixed negative bias applied to its control grid 14 from a suitable source such as a battery 16.

In order to provide gain control for the video amplifier, a variable cathode resistor 17 is connected between the cathode 18 of the pentode and ground, this resistor having no bypass condenser whereby there is a certain amount of degeneration, depending upon the value of the resistor. Therefore, a change in the resistance value of the cathode resistor changes the gain of the video amplifier 12. Such a gain control in a television receiver is also referred to as a "contrast control."

The receiver also includes the usual horizontal and vertical deflecting circuits 19 and 21 which are synchronized by the incoming synchronizing pulses for the purpose of keeping the scanning at

the cathode ray tube in synchronism with the scanning at the transmitter.

In accordance with my invention, in order to supply the synchronizing pulses to the deflecting circuits 19 and 21, the composite signal consisting of picture signals and synchronizing pulses is taken off the output circuit of the video amplifier 12 even though this amplifier contains a gain or contrast control and supplied through a suitable synchronizing amplifier 22 to a separating tube 23 or separating circuit which passes only the synchronizing pulses to a filter circuit 24. Suitable filter circuits are well known in the art and preferably comprise resistor and capacitor networks so arranged that the horizontal and vertical deflecting pulses are separated from each other.

In the example illustrated, the synchronizing amplifier 22 is a triode having in its input circuit a grid condenser 26 and a grid resistor 27 of such capacity and resistance values that the tube is grid-leak biased. It will be noted that the picture signals, since they are of positive polarity at this point in the circuit, drive the grid positive to provide the bias. This, of course, results in picture signal distortion but since the picture signals are to be removed by the synchronizing separator tube anyhow, this is immaterial. It will be understood that the amplifier 22 may be biased in any other suitable manner, for example, in the same way as the video amplifier 12.

Since, with the connection above described, any change in the contrast control of the video amplifier will change the amplitude of the synchronizing pulses supplied to the synchronizing amplifier, and, since it is very desirable that there be no great variation in the amplitude of the synchronizing pulses when applied to the synchronizing separator 23, the synchronizing amplifier 22 is provided with a gain control which, in the example illustrated, consists of a variable cathode resistor 28 connected between the cathode 29 of the triode and ground. The variable resistor 28 and the variable gain control resistor 17 of the video amplifier are ganged or mechanically coupled together in such a way that, when the cathode resistor 17 of the video amplifier is changed to increase the gain of this amplifier, the resistance of the other cathode resistor 28 in the synchronizing amplifier is changed in the opposite sense in order to reduce the gain of this amplifier. These changes in resistance of the two cathode resistors are so related that, regardless of change in gain in the video amplifier 12, it does not affect substantially the amplitude of the synchronizing pulses as they appear in the output circuit of the synchronizing amplifier 22.

The synchronizing separator tube 23, to which the amplified synchronized pulses and picture signals are applied, preferably is of the grid-leak biased type described and claimed in application Serial No. 23,136 filed May 24, 1925, in the name of William A. Tolson, and assigned to Radio Corporation of America. It will be noted that this preferred type of separating tube requires that the synchronizing pulses be applied to its grid with positive polarity. It will be apparent, therefore, that, if the usual practice were followed in the receiver illustrated, the synchronizing signals for the synchronizing channel would be taken off the second detector 10 and a second synchronizing amplifier stage would be required in order to reverse the polarity of the synchronizing pulses.

In Fig. 3, curves are shown which give the

necessary design information for the gain control resistors 17 and 28 for the case where the particular amplifier tubes of the types indicated in Fig. 3 are employed. It will be noted that in this specific example these curves are for a design where the resistance of the cathode resistors 17 and 28 is varied by rotating an arm in contact with resistance material, the arms of the two variable resistors being connected to a rotatable shaft which may be rotated by means of a contrast control knob on the panel of the receiver.

In Fig. 2 there is illustrated another embodiment of my invention which is the same in principle as the embodiment above described. In this embodiment, however, the design is simplified by connecting the cathodes of the video amplifier 36 and synchronizing amplifier 37 together by means of a cathode resistor 38 which has a variable contact point 39 thereon through which connection is made to ground.

In this arrangement, as in the one previously described, the gain of the video amplifier 36 and of the synchronizing amplifier 37 is controlled by means of degeneration. It will be apparent from an inspection of Fig. 2 that if the variable tap 39 is moved in a direction to increase the resistance of the cathode resistor for the video amplifier 36 and thereby decrease the gain of the amplifier, the cathode resistance for the synchronizing amplifier 37 will simultaneously be decreased thereby simultaneously increasing the gain of the synchronizing amplifier.

It will be apparent that the circuit of Fig. 2 operates similar to the circuit of Fig. 1 to maintain the amplitude of the signal output of the synchronizing amplifier substantially constant regardless of changes made in the gain of the video amplifier. It may be noted that in general the embodiment shown in Fig. 1 is preferred, since it permits greater flexibility in design. In receiver designs where low cost is a more important consideration, however, the design illustrated in Fig. 2 may be preferred.

While I have shown and described a degenerative type of circuit for controlling the gain of the video and synchronizing amplifiers, it should be understood that other well-known gain control circuits may be employed instead.

I claim as my invention:

50. 1. In a television receiver comprising a cathode ray tube and associated deflecting circuits for deflecting the cathode ray, means for demodulating a carrier wave which is modulated by picture signals and synchronizing pulses, a video amplifier connected between said demodulating means and said cathode ray tube, said video amplifier comprising a stage having gain control means, a synchronizing amplifier stage; means for separating picture signal from synchronizing pulses, said synchronizing amplifier stage and said separating means being connected in the order named between said video amplifier and said deflecting circuits, the synchronizing amplifier being connected to said video amplifier at a point following said gain control means, gain control means for said synchronizing amplifier stage, and means for so ganging said two gain control means that the output of the synchronizing amplifier remains substantially constant regardless of changes in the gain of said video amplifier.

60. 2. In a television receiver comprising a cathode ray tube and associated deflecting circuits for deflecting the cathode ray, means for demodulating a carrier wave which is modulated

by picture signals and synchronizing pulses, a video amplifier connected between said demodulating means and said cathode ray tube, said video amplifier comprising a stage having gain control means, a synchronizing amplifier stage, said synchronizing amplifier stage being connected between said video amplifier and said deflecting circuits, the synchronizing amplifier being connected to said video amplifier at a point following said gain control means, and means for changing the gain of the synchronizing amplifier in one sense in response to changing the gain of the video amplifier in the opposite sense.

3. In a television receiver comprising a cathode ray tube and associated deflecting circuits for deflecting the cathode ray, means for demodulating a carrier wave which is modulated by picture signals and synchronizing pulses, a single video amplifier stage so connected between said demodulating means and said cathode ray tube as to have synchronizing pulses of negative polarity in its output, said amplifier stage having gain control means, a single synchronizing amplifier stage, a grid-leak-biased tube for separating picture signal from synchronizing pulses, said synchronizing amplifier stage and said separating tube being connected in the order named between the output circuit of said video amplifier stage and said deflecting circuits, gain control means for said synchronizing amplifier stage, and means for so ganging said two gain control means that changing the gain of said video amplifier in one sense causes a change in gain in the synchronizing amplifier in the opposite sense.

4. In a television receiver comprising a cathode ray tube and associated deflecting circuits for deflecting the cathode ray, means for demodulating a carrier wave which is modulated by picture signals and synchronizing pulses, a

single video amplifier stage so connected between said demodulating means and said cathode ray tube as to have synchronizing pulses of negative polarity in its output, said amplifier stage having gain control means consisting of a variable cathode resistor, a single synchronizing amplifier stage, means for separating picture signal from synchronizing pulses, said synchronizing amplifier stage and said separating means being connected in the order named between the output circuit of said video amplifier stage and said deflecting circuits, said synchronizing amplifier stage having gain control means consisting of a variable cathode resistor, and means for so ganging said two gain control means that changing the gain of said video amplifier in one sense causes a change in gain in the synchronizing amplifier in the opposite sense.

5. In a television receiver comprising a cathode ray tube and associated deflecting circuits for deflecting the cathode ray, means for demodulating a carrier wave which is modulated by picture signals and synchronizing pulses, a single video amplifier tube so connected between said demodulating means and said cathode ray tube as to have synchronizing pulses of negative polarity in its output, a single synchronizing amplifier tube, means for separating picture signal from synchronizing pulses, said synchronizing amplifier tube and said separating means being connected in the order named between the output circuit of said video amplifier tube and said deflecting circuits, said amplifier tubes having cathodes which are connected to each other 30 through a resistor, and a grounded variable tap on said resistor whereby a change in the position of said tap changes the gain of said video amplifier in one sense and changes the gain in the synchronizing amplifier in the opposite sense.
